US00D483074S

(12) **United States Design Patent** (10) Patent No.: **US D483,074 S**
Strunk et al. (45) Date of Patent: ** Dec. 2, 2003

(54) **DISPLAY APPARATUS**

(75) Inventors: **David D. Strunk**, Weddington, NC (US); **Aaron D. Kephart**, Charlotte, NC (US)

(73) Assignee: **Bank of America Corporation**, Charlotte, NC (US)

(**) Term: **14 Years**

(21) Appl. No.: **29/158,842**

(22) Filed: **Apr. 12, 2002**

(51) LOC (7) Cl. **20-02**

(52) U.S. Cl. **D20/41**

(58) Field of Search D20/10, 19, 39, D20/40, 41, 99; D26/34; D99/28; 40/559, 584, 607, 611; 707/1
